The ornamental design for a ventilator channel, as shown and described.

DESCRIPTION

FIG. 1 is a front perspective view of the ventilator channel.

FIG. 2 is a rear perspective view of the ventilator channel.

FIG. 3 is a front view of the ventilator channel.

FIG. 4 is a right side view of the ventilator channel.

FIG. 5 is a rear view of the ventilator channel.

FIG. 6 is a left side view of the ventilator channel.

FIG. 7 is a top view of the ventilator channel.

FIG. 8 is a bottom view of the ventilator channel; and,

FIG. 9 is a bottom view of the ventilator channel without the broken line portions of FIG. 8.

The features shown in broken lines depict environmental subject matter only and form no part of the claimed design.
